UNITED STATES PATENT OFFICE.

HENRY L. GUENTHER, OF LOS ANGELES, CALIFORNIA.

CAN-CAP FEED.

Application filed December 21, 1921. Serial No. 523,824.

To all whom it may concern:

Be it known that I, HENRY L. GUENTHER, a citizen of the United States, residing at Los Angeles, in the county of Los Angeles 5 and State of California, have invented new and useful Improvements in Can-Cap Feeds, of which the following is a specification.

In can capping machines it is desirable that a cap shall be automatically fed to a 10 can as it in turn is fed into the machine and afterwards double seamed.

In most cap feeding machines the caps are fed consecutively irrespective of the feed of cans to the machine and it is the 15 principal object of the present invention to provide an automatically operated mechanism which will insure that a can cap will only be fed to the machine co-incidentally with the feeding of a can thereto, and the 20 cap and can will thereafter be delivered to the machine in positions relative to each other to insure that they will be double seamed.

The present invention contemplates the 25 use of a can cap stack member adapted to hold a plurality of caps in superposed relation to each other and from the bottom of which device the caps may be successively fed, such member being disposed above the 30 path of travel of cans to the first operation turret of a double seaming machine of the type generally indicated in my co-pending application entitled "Double seaming machine," filed concurrently herewith. Means 35 are provided to feed the lowermost cap from the stack and this means is supplied with automatically operated mechanism adapted to insure that a cap will only be fed when a can is about to pass through the feed 40 mechanism.

The invention is illustrated by way of example in the accompanying drawings, in which:

Figure 1 is an enlarged fragmentary view 45 in plan showing the first seaming turret and the means for feeding a can thereto, including the can cap mechanism.

Fig. 2 is an enlarged fragmentary view 50 showing the trip device of the can cap feed.

Fig. 3 is an enlarged fragmentary view 55 in vertical section and elevation showing the device disclosed in Fig. 2.

Referring more particularly to the drawing, 10 indicates a horizontally disposed feed disc along which can bodies may be caused 55 to travel and by which they will be moved

toward the end of a double seaming machine. This machine is here shown as provided with a rotary turret structure 11 for receiving the cans and caps and for thereafter acting upon them to form a double seam between a can and its cap, the mechanism of which device is not shown in the drawing. The portion 60 of the first seaming turret as indicated in the drawing comprises a feed spider 12 formed with a plurality of semi-circular recesses 13. These recesses occur at the ends of arms and are of such dimension as to substantially conform to the circumferential face of a can body. The tops of these recesses are counter-bored as indicated at 14 to receive a can cap, and in addition to this, feed blades 15 are 65 secured to the rear-most edges of the recesses 14 to feed the can caps forwardly and to carry them with the can bodies seated within 70 the recess. 75

Partially circumscribing the turret structure 11 is a track 16. This track acts as a 80 guide rail for the can caps and supports them as they are fed forwardly by engagement with the blades 15.

Secured directly above the feed spider 12, and in the path of rotation of the cans is a frame structure 17. This structure supports vertical posts 18, between which a 85 stack of can caps 19 are held, and a base plate 20 holds the posts 18. This plate has a central opening therethrough, of a size to permit the can caps to fall onto the track 16. Slide-ways are formed between the frame 90 member 17 and the plate 20. These receive plates 21, one of which is disposed at each side of the can stack. The innermost edges of these plates normally support the stack of cans and are formed with blade portions 95 which will cut the lowermost cap from the stack, it being understood that the plates 21 simultaneously reciprocate in a horizontal plane beneath the stack of caps. The two plates are secured together by a cross-head 100 22. This head carries a central push finger 23 which engages the rear edge of the lowermost can cap and feeds it forwardly.

A pitman rod 24 is pivotally secured to the crosshead 22 at its forward end, and to 105 a lever arm 25 at its rear end. The movement of this rod produces reciprocation of the feed plate. The lever 25 is fixed to a vertical pin 26. This pin is formed with an enlarged lower portion 27, as more clearly 110 shown in Fig. 3. A recess 28 is formed in the circumferential edge of the portion 27

and may receive a pawl 29 under certain conditions as will be hereinafter described. The lower portion of the pin 26 is freely mounted for rotation in a cup member 30. This 5 member is pinned to a positive drive shaft 31. The cup member 30 carries the pawl 29, as will more clearly be seen in Fig. 2. An expansion spring 32 is provided to normally hold the engaging end of the coil against the 10 side face of the pin 26 to insure that it will pass into the recess 28 when in register therewith. Suitable gear means are operatively connected with the pin 26 and continuously drives the pin.

15 A star wheel 33 is provided to transfer the cans from the rotary feed disc 10 to the spider 12 of the turret 11. This wheel is here shown as formed with three recess arms adapted to conform to the circumference of 20 the can and to hold it in the recess 13 of an adjacent arm on the spider 12. It will be understood that the cans are fed from the disc 10 and are carried along a stationary feed table 34 as guided by the arm of the 25 star wheel 33 and guide rails 35. These guide rails pass over the disc and partially over the stationary feed table. As before stated, it is the principal object of the present invention to insure that a can top will 30 only be delivered from the stack when a can body is being fed into the machine and in such synchronism as to insure that it will register with the fed can cap. This feeding will be brought about by the star wheel 33 and will be supplemented by the spider 12. In order to insure that a "no can, no cap feed" will result, an enlarged bell crank 36 is provided. This bell crank is suitably pivoted to the fixed floor of the machine and 40 has a curved arm 37 extending along the track 35. This arm normally extends into the path of the passing can and will be depressed by the movement of the can along the track 35, as fed by the star wheel 33.

45 The opposite arm of the bell crank 36 is indicated at 38. This arm is straight and has an end portion normally engaging the outer free end of the pawl 29, the pawl and arm being so designed as to normally hold the pawl out of engagement with the recess 28, except when the arm 37 is depressed. A spring 40 acts to yieldably hold the bell crank in a position so that the arm 37, is in 50 the path of travel of the can.

55 In operation of the present invention cans may be suitably fed onto the feed disc 10, and as this disc rotates in the direction of the arrow —a—, the cans will find their way between the guide rails 35 and the 60 guide rails 41. Here they will be successively engaged by arms of the star wheel 33 and will be carried along (while held against the guide rails 35) into register with recess 13 of one of the arms of star wheel 12. It 65 is to be noted that the star wheel 33 and the

turret 11 are geared to travel in synchronism, thus insuring that the recess portion of the star wheel and the recesses 13 of the spider 12 will always register and suitably hold the can body as it is carried forward. 70 When the star wheel 33 and the feed spider 12 have reached the position shown in the drawing the star wheel will recede from its feeding position and the can body will then engage a guide rail 16, previously mentioned, along which it will be further carried by the action of the spider 12. This action will not have been brought about, however, until after the can body has encountered the arm 37 of bell crank 36. At 80 this time the arm will be depressed to conform to the contour of the guide rails 35 and this will swing the long lever arm 38 of the bell crank into the direction of the arrow —b—, thus relieving the pawl 29. 85 The spring 32 will then depress the pawl against the circumferential face of the member 27 and when the cup 30 and the pawl proceed to travel around the pin 26 the end of the pawl will register with the recess 28 and lock so that the pin will be rotated. 90 This motion will be imparted to the lever arm 25 and the pitman rod 24. A complete rotation of the lever arm around the pin axis will then take place, and this will produce alternate reciprocation of the feed plates 21. When the cup 30 and its pawl 29 again reach the position of the lever 38 the pawl will be removed from its recess and the pin 26 will remain motionless unless it so happens that another can body is being fed past the lever 37, in which instance the pawl will remain in engagement and continue to insure that can caps will be simultaneously fed to the passing can bodies. 100

As the can body passes beneath the stack of can caps 12, one cap will be fed forwardly to the position indicated by dotted line at C. This cap will be engaged by the blade 15 following the can body, and will carry the cap along the guide track 16 and into the machine. 110

It will thus be seen that the present invention insures that a continuous feed operation may be brought about so that can bodies may be rapidly and successively fed into a machine and at the same time the can caps may be co-incidently delivered to each of the can bodies passing beneath a stack of can caps and otherwise insure that when, 115 for any reason, the flow of can bodies is discontinued the cap feed will also be discontinued. 120

While I have shown the preferred form of my invention as now known to me, it will be understood that various changes in the construction, combination and arrangement of parts may be made by those skilled in the art, without departing from the spirit of the invention as claimed. 125

130

Having thus described my invention, what I claim and desire to secure by Letters Patent is:

1. In combination with a can seaming machine, a cap feed comprising positively operating means for successively feeding filled cans to a machine, and means for delivering a cap to each of the cans carried by said positive feed means, said cap delivering means including continuously operating driving means, can cap actuating means, and mechanism for connecting the can cap actuating means to the driving means, and means directly operated by a can for actuating the said mechanism.
2. In combination with a can seaming machine, a cap feed comprising positively operating means for successively feeding filled cans to a machine, and means for delivering a cap to each of the cans carried by said positive feed means, said cap delivering means including a continuously rotating driving shaft, can cap actuating means, a clutch for connecting the cap actuating means and the continuously rotating shaft, and means directly engaged by the cans for operating the clutch.
3. In combination with a can seaming machine, a cap feed comprising positively operating means for successively feeding filled cans to a machine, and means for delivering a cap to each of the cans carried by said positive feed means, said cap delivering means including a continuously rotating shaft, can cap actuating means, a clutch for connecting the cap actuating means with the continuously rotating shaft, and means directly engaged by the cans for operating the clutch.
4. In combination with a can seaming machine, a cap feed comprising positively operating means for successively feeding filled cans to a machine, and means for delivering a cap to each of the cans carried by said positive feed means, said cap delivering means including reciprocating can cap actuating means, a crank element connected therewith, a continuously rotating shaft, mechanism for connecting the crank element with the continuously rotating shaft, and means directly operated by a can for actuating the said mechanism.
5. In combination with a can seaming machine, a cap feed comprising positively operating means for successively feeding filled cans to a machine, and means for delivering a cap to each of the cans carried by said positive feed means, said cap delivering means including reciprocating can cap actuating means, a crank element connected

therewith, a continuously rotating shaft, a clutch for connecting the crank element with the continuously rotating shaft, and means directly engaged by the cans for operating the clutch.

6. In combination with a can seaming machine, a cap feed comprising positively operating means for successively feeding filled cans to a machine, and means for delivering a cap to each of the cans carried by said positive feed means, said cap delivering means including reciprocating can cap actuating means, a crank element connected therewith and having a spindle, a continuously rotating shaft provided with a cup receiving the spindle, a spring pressed pawl constituting a clutch for connecting the spindle with the continuously rotating shaft, said shaft having means for cooperating with the pawl, and means directly engaged by the cans for operating the pawl.

7. In combination with a can seaming machine, a cap feed comprising positively operating means for successively feeding filled cans to a machine, and means for delivering a cap to each of the cans carried by said positive feed means, said cap delivering means including reciprocating can cap actuating means, a crank element connected therewith and having a spindle, a continuously rotating shaft provided with a cup receiving the spindle, a pawl constituting a clutch for connecting the spindle with the continuously rotating shaft said shaft having means cooperating with the said pawl and the latter being movable into and out of engaging position, yieldable means for urging the pawl into its engaging position, and a lever extending into the path of the cans and adapted to be operated by the same and having an arm arranged to normally hold the pawl out of engagement with the spindle.

8. In combination with a can seaming machine, a cap feed comprising positively operating means for successively feeding filled cans to a machine, and means for delivering a cap to each of the cans carried by said positive feed means, said cap delivering means including spaced reciprocating plates for supporting the can caps, a finger operating between the plates for actuating the can cap to feed the same, a crank element connected with the said plates and the finger, a continuously rotating shaft, mechanism for connecting the crank element with the continuously rotating shaft, and means directly engaged by the cans for operating the said mechanism.

HENRY L. GUENTHER.
